Primary Examiner — Adam C Mager(74) *Attorney, Agent, or Firm* — Reising Ethington P.C.(57) **CLAIM**

The ornamental design for a vehicle wheel front face, as shown and described.

DESCRIPTION

FIG. 1 is a front perspective view of the vehicle wheel front face showing my design;

FIG. 2 is a front elevation view thereof; and,

FIG. 3 is a side elevation view thereof.

The broken lines in the drawings are for the purpose of illustrating environmental structure that form no part of the claimed design.
